UNITED STATES PATENT OFFICE

168,605

AIRPLANE

Willem D. van Zelm, Ruxton, Richard K. Wentz,
Baltimore, and Ralph H. Draut, Kingsville, Md.,
assignors to The Glenn L. Martin Company,
Baltimore, Md.

Application August 24, 1950, Serial No. 11,904

Term of patent 14 years

(Cl. D71--1)

To all whom it may concern:

Be it known that we, Willem D. van Zelm, Richard K. Wentz, and Ralph H. Draut, citizens of the United States, and residents, respectively, of Ruxton, county of Baltimore, State of Maryland; city of Baltimore, State of Maryland and Kingsville, county of Baltimore, State of Maryland, have invented a new, original, and ornamental Design for an Airplane, of which the following is a specification, reference being had to the accompanying drawings, forming a part thereof.

Figure 1 is a top perspective view of an airplane showing our new design.

Figure 2 is a bottom perspective view thereof.

Figure 3 is a top plan view of the airplane.

Figure 4 is a front view thereof, and

Figure 5 is a side view thereof.

The characteristic features of our design reside in the parts shown by full lines in the drawing.

We claim:

The ornamental design for an airplane, substantially as shown and described.

WILLEM D. VAN ZELM.
RICHARD K. WENTZ.
RALPH H. DRAUT.
